WASHING MACHINE

Charles S. Bossie, New York, N. Y., assignor to
 Perfection Appliances, Inc., New York, N. Y., a
 corporation of New York

Application September 22, 1932, Serial No. 634,327

4 Claims. (Cl. 259—112)

This invention relates to a washing machine, and is an improvement of the washing machine described in my patent for washing machine, No. 1,896,347, dated February 7, 1933.

5 The object of the invention is the production of a washing machine which can be easily positioned in a washtub or other receptacle when in use, and the parts of which can be folded to completely position the washing machine in the 10 washtub or other receptacle when not in use.

The second object of the invention is the production of a washing machine which can be unfolded and locked in operative position.

The third object of the invention is the production of a washing machine which is automatically adjustable when operating with various 15 quantities of clothing in a washtub or other receptacle.

The fourth object of the invention is the production of a washing machine having a flexible 20 element, that coacts with the folding and unfolding appurtenances of the machine.

The fifth object of the invention is the production of a washing machine containing appurtenances to reduce the amount of splashing 25 to a minimum.

The sixth object of the invention is the production of a washing machine for washing clothing or other fabrics easily, and which avoids filling the machine with water and drawing the same therefrom.

In the accompanying drawings Fig. 1 represents a front elevation of an exemplification of the improved washing machine in operative position, with the cover thereof in section; Fig. 2 shows a left-hand side view of Fig. 1 with a sectional view of the washtub in which the machine is positioned; Fig. 3 indicates a partial rear view of Fig. 1 with a portion of the cover of the machine broken away; Fig. 4 represents a top view of the washing machine with its cover in horizontal section; Fig. 5 is a view similar to Fig. 2 with the machine in its folded position; Fig. 6 indicates a section of Fig. 1 on the line 6, 6; Fig. 7 is a section of Fig. 1 on the line 7, 7; Fig. 8 shows a section as on the line 8, 8 of Fig. 3; Fig. 9 indicates a section of Fig. 3 on the broken line 9, 9; Fig. 10 shows a partial front view of the washing machine with its clothes wringer connected thereto; Fig. 11 indicates a left-hand side view of Fig. 10 partly in vertical section and Fig. 12 represents a wiring diagram of the washing machine.

The washing machine in this instance is indicated to comprise a platform designated in its

entirety by the numeral 20. Extending up from platform 20 is indicated a gear housing 22, comprising the front wall 23, the rear wall 24 and the side walls 25. A cover 28 is bolted to the top faces of the walls of the gear housing. Supporting blocks 30 are integral with and extend up from the platform 20 and are indicated with the journal bearings 31. Ribs 32 extend up from the platform 20 and connect one of the walls 25 of the gear housing 22 and the blocks 30. Journal 10 bearings 33 are indicated in the walls 23 and 24 of the gear housing 22.

A tapered indentation 34, Fig. 11 is indicated in the outer face of the wall 23. Journal bearings 35 are indicated in the walls 25. An electric 15 motor is indicated in its entirety by the numeral 40, and its feet 41 are bolted to the supporting blocks 30. The armature shaft of the electric motor is indicated at 42.

In the journal bearings 35, see Figs. 1 and 4, is 20 journaled the worm shaft 43, which has secured thereto the thrust collars 44. A worm 46 is fastened to the worm shaft 43, and roller bearing cages 47 are supported on the shaft 43 between thrust collars 44 and the ends of the said worm 25 46. The armature shaft 42 and the worm shaft 43 are detachably connected to each other by the coupling 50. In the journal bearings 33 is journaled the shaft 51, which at its front end has integral therewith the locking projection 52 with 30 the flat side faces 53. The worm wheel 54 is fastened to the shaft 51 and is in mesh with the worm 46. To the shaft 51 is fastened one end of the arm 57, see Figs. 3 and 4. In the journal bearings 31 is journaled the oscillating cross shaft 35 58, to which is fastened one end of the arm 59. A link 60 connects the arms 57 and 59. To the front end of the shaft 58, see Figs. 1, 2 and 6, is fastened the supporting collar 65 having the flat side faces 66. To the front face of the supporting collar 40 65 is bolted the locking lever 67 and pins 67a extend from the lever 67.

To the front wall 23, see Figs. 1, 4, 10 and 11, of the gear housing 22 is bolted the U shaped bracket 68, having the front wall 69 with the vertical slots 45 70.

A detachable cover 72 having the front wall 73, the rear wall 74 and the side walls 75 and 76, is fastened to the platform 20 by means of the screws 77. In the rear wall 74 of the cover 72 are 50 indicated the ventilating openings 78.

An opening 79 is indicated in the front wall 73 for the supporting collar 65. From the front wall 73 of the cover 72 extends the upper guide pin 80, and to said wall are attached the double pole 55

starting switch 82, the double pole reversing switch 83. To the side wall 25 is fastened a cap 84 over an opening in line with the worm shaft 43. To the said front wall 73 are also bolted the 5 brackets 88, which support the handle 90. The bracket 91 is fastened to and depends from the platform 20, and has extending therefrom the lower guide pin 92.

An upper oscillating beam, see Figs. 1, 2, 3, 4, 10 and 7 is indicated in its entirety by the numeral 95, and is shown with the hub portion 96, having the vertical opening 97. End hubs for the beam 95 are indicated at 98. A lower oscillating beam is indicated at 99, which is similar to the beam 15 95, and is shown with the vertical opening 100, similar to the opening 97. A hub portion is shown at 101 and hub ends are indicated at 102 for the lower oscillating beam 99.

In the hub ends 98 are supported the supporting pins 106, with the washers 107 and the lock washers 108. In the hub ends 102 are supported the supporting pins 110 similar to 106, with its washers 111 and 112, similar to 107 and 108. Stems 115 are pivoted on the pins 106 and 110. 25 Screws 116 are in engagement with the pins 106 and 110 to maintain the stems 115 in place. Integral with the lower end of each of the stems 115 is indicated the housing 120, in which is slidably positioned the cup shaped sleeve 121, with the 30 lower enlarged end 122, having the exterior thread 123 formed therewith. A bolt 125 is shown with the head 126, and extends through an opening in the enlarged end 122 and its upper end is in threaded engagement with the upper end of the 35 housing 120. A spring 127 is supported on the bolt 125 and bears between the housing 120 and the enlarged end 122, of the sleeve 121.

Suction plungers are each indicated with their hood shaped shells 130. Each of said shells is 40 shown with the neck 131 having the thread 132, which engages the thread 123 of one of the sleeves 121.

At the lower end of each shell 130 is indicated the turned up flange 133, and adjacent to the latter is shown the outwardly extending locking flange 134. For each of the suction plungers is indicated the cup shaped lower head 135 having the bottom wall 136, with the openings 137, and the circular stepped side wall 138, having the 45 locking flange 139 at its upper end. Openings 140 are indicated in the side wall 138. The head 135 is detachably connected to its shell 130, by springing the flange 139 into the locking flange 134. It will be noted that an annular cavity 141 is 50 formed between the side wall 138 and the shell 130.

A pair of supporting brackets are designated in their entireties by the numerals 144 and 145. The said supporting brackets are each indicated 55 with the upper horizontal flange 146 having the bevel edge 146a, the longitudinal rib 147 and the cross rib 148. An elongated slot 150 is indicated in each of the flanges 146. Bolts 151 extend through the slots 150 and engage threaded openings in the platform 20. By means of the elongated slots 150 in the brackets and the bolts 151, the brackets 144 and 145 can be laterally clamped in different positions. At the lower ends of each of the said brackets 144 and 145 is formed the bifurcated hub 152. A lug 153 having the bearing faces 153a and 153b is indicated above each of the hubs 152. A horizontal guide sleeve 154 and the vertical guide sleeve 155 are formed with each lug 153.

75 An eyelet 162 extends from each flange 146.

An opening 163 is formed in each rib 148 and an opening 164 is formed in each longitudinal rib 147. In each horizontal guide sleeve 154 is slidably positioned a pin 168, having the pair of locking grooves 169 and 170 at one end. In each vertical guide sleeve 155 is positioned the helical spring 171, at the upper end of which is supported the ball 172. At the lower end of the sleeve 155 is supported the screw plug 173, which in turn supports the spring 171. The ball 172 is adapted to 10 engage the grooves 169 and 170.

A pair of similar triangular shaped supporting legs are indicated in their entireties by the numerals 180 and 181. Each of said supporting legs comprises the vertical member 184, which at its upper end has integral therewith the projecting lug 185, having the flat bearing face 185a, and the hub 186 having a threaded opening. In each of the latter threaded openings is supported a screw 187 with the bumper head 188 preferably of rubber. A nut 189 on the screw 187 clamps the latter in place. At the lower end of the vertical member 184 is indicated the hub 192, having an axial threaded opening for the screw 195, supporting the bumper head 196. A nut 197 on the screw 195 clamps the latter in place. Each of the legs 180 and 181 has also integral therewith the inclined member 200, having the vertical lower rib 201, and the vertical upper rib 201a, which connect the inclined member 200 with the vertical member 184. A journal lug 202 is integral with the upper portion of the member 184. A bifurcated stop lug 203 having the upper face 203a is integral with the upper end of the inclined member 200, and at its lower end is formed the 30 hub 204. A bumper foot 205 preferably of rubber has extending therefrom the screw 205a, which is in threaded engagement with a threaded opening in the hub 204. A locking heel 206 is formed with the inclined member 200. A lug 207 extends from the upper end of each vertical member 184, and has journaled thereto the flanged roller 208. A lug 212 extends from each rib 201. A journal pin 215 connects the bifurcated hubs 152 and the lugs 202. A flexible steel band 220 has one end connected to the eyebolt 162, leads over the flanged roller 208, and is connected to the spring 221. The latter is fastened to the lug 212, by means of the screw 222.

A locking pawl 225 is indicated with the bifurcated bearing 226, at its upper end and the bifurcated locking heel 227 at its lower end.

Ribs 228 extend from the sides of the pawl 225 and at their upper ends terminate in the bearing faces 229, that are adapted to bear against the 55 faces 153a of the lugs 153.

A pin 230 connects the bifurcated bearing 226 with its accompanying rib 148. A spring 232 is wound around the pin 230 with one end thereof extending through its accompanying opening 164 60 in its adjacent rib 147. A hook end 233 is formed with the spring 232 to connect it to said rib 147. The other end 234 of the spring 232 extends through openings in the bifurcated bearing 226. The spring 232 functions to maintain the bifurcated locking heel 227 locked to the locking heel 206.

For the supporting leg 180 there extends from the longitudinal rib 147 of its accompanying bracket 144, the journal pin 240, which is held in place by the bolt 241. A separator plate 242, having the handle 243 is supported on the bolt 241. A pin 244 extends from the rib 147 in the path of the separator plate 242. The plate 242 is adapted to bear between the bearing faces 153b and 185a. 75

A clothes wringer is indicated in its entirety by the numeral 250, see Figs. 10 and 11. Side walls of the wringer are shown at 252 and 253. Rollers 254 and 255 have their shafts, one of which is shown at 256, journaled in side walls of the wringer. From one end of the shaft 256 extends a locking projection 257 having opposite flat sides 260. To the wall 252 is fastened the spacer pin 263 having a tapered end 264 which is adapted to be seated in the tapered indentation 34. A pair of supporting pins 265 having the flange collars 266 at their outer ends extend from the wall 252 of the wringer, and are adapted to be seated in the vertical slots 70. A locking sleeve, see Figs. 1, 10 and 11 shown at 270 is indicated with an opening at one end having the flat faces 271, and an opening at its other end having the flat faces 272 at right angles to the flat faces 271. When the washing wringer is located in place the pins 265 are supported in the vertical slots 70, and the end 264 of the spacer pin 263 is seated in the tapered indentation 34. The locking sleeve 270 is positioned with the flat faces 272 of one of its openings engaging the flat side faces 53 of the locking projection 52, and the flat faces 271 of its other opening engaging the flat side faces 260 of the locking projection 257.

The wash tub 279 in this instance is indicated having the side walls 280, the rear wall 281, the bottom wall 282 having an opening for the outlet plug 284, and the inclined front wall 285, having the curved portion 286 connecting it with the bottom wall 282.

Referring to the wiring diagram indicated in Fig. 12, the electric motor is indicated at 40, the source of electric current in this instance an electric battery is shown at 290, and the double pole starting switch is shown at 82 and the double pole reversing switch is shown at 83. A wire 291 connects the battery 290 and one of the members of the switch 82 and a wire 292 connects the battery 290 and the other member of the switch 82. Terminals are shown at 295 and 296, 297, 298, 299 and 300. A wire 303 connects the terminal 295 and one of the members of the reversing switch 83. A wire 304 connects the terminal 296 and the other member of the reversing switch 83. A wire 305 connects the terminal 299 and the electric motor 40, and a wire 306 connects the terminal 300 and the electric motor 40. A wire 308 connects one of the members of the reversing switch 83 and the electric motor 40, and a wire 309 connects the other member of the reversing switch 83 and said electric motor 40.

The washing machine when not in use is in folded position as indicated in Fig. 5, the bumper heads 188 and 196 and the bumper foot 205 bearing respectively against the rear wall 281 and the curved portion 286 of the front wall 285 of the wash tub 279, to maintain the platform 20 in a vertical plane.

To locate the washing machine in operative position, it is pulled up by grasping the handle 90 of the cover 72, until the bifurcated locking heel 227 of the locking pawl 225 locks with the locking heel 206 of the inclined member 200, see Figs. 1, 2, 3 and 9. It will be noted that at this time the separator plate 242 is positioned between the bearing face 153b of the lug 153 and the bearing face 185a of the lug 185.

The springs 221 with their bands 220 assist in unfolding the washing machine.

The clothes to be washed, the soap and the water or other fluid are located in the wash tub 279. The switch 83 is now positioned to locate

the appurtenances of the motor for rotation in one direction or the opposite thereto. Next the switch 82 is positioned to start the electric motor 40. With the rotations of the armature shaft 42 of the electric motor 40, the worm shaft 43 with the worm 46 is turned and thereby the worm wheel 54 is turned. The rotations of the shaft 51 of the worm wheel revolves the arm 57, which oscillates the link 60 and the arm 59. Thereby the oscillating cross shaft 58 is oscillated. By this means the stems 115 with their suction plungers having the shells 130 are reciprocated and beat the clothing in the wash tub 279. A partial vacuum is made between the plungers and the clothing when the plungers rise. The openings 137 and 140 in the head 135 break the said vacuum when the plungers are spaced from the fluid in the wash tub, which allows the clothing to drop, which further agitates said clothing and circulates the water through them. The annular space 141 between the lower portion of each suction plunger having the shell 130 and its head 135, prevents the water in the wash tub 279 splashing upwardly. If there is excessive pressure against the lower heads 135, the springs 127 will be compressed and cause the suction plungers having the shells 130 to move upwardly and relieve the pressure.

Referring particularly to Fig. 1, the oscillating beam 95 is oscillated by the oscillating cross shaft 58, through the intervention of the supporting collar 65, the flat side faces 66 coacting with the vertical opening 97 in the hub portion 96 of the upper oscillating beam 95. If an abundance of material to be washed is in the wash tub 279, the lower oscillating beam 99, is positioned with the opening 100 of the hub portion 101 in contact with the flat side faces 66 of the collar of the oscillating shaft 58, and the opening 97 of the hub portion 96 is in contact with the guide pin 80. After the clothing has been beaten by the suction plungers 130 the water is drawn from the wash tub, the electric motor 40 is stopped, the oscillating beams 95 and 99 with their suction plungers having the shells 130 are removed, and the clothes wringer 250 is placed in operative position, by means of the supporting pins 265 and the spacer pin 263. The locking sleeve 270 is placed in position to connect the shaft 256 and the shaft 51.

The motor 40 is again started to turn the rollers 254 and 255 of the clothes wringer 250.

After the clothing has been wrung, the clothes wringer is disconnected. The machine is now again folded in the wash tub 279. This is accomplished by first swinging up the separator plate 242 in the direction of the arrow A, Fig. 3. The operator next slightly tilts the washing machine toward the rear wall 281 of the wash tub 279 by grasping the handle 90 and the pins 168 are moved toward the bearing face 229 of the locking pawl 225 until the ball 172 is engaged with the locking groove 170, and the locking heel 227 is disengaged from the locking heel 206. The operator by controlling the handle 90 allows the machine to swing down on the journal pins 215, the locking heel 227 sliding on the rib 201a until the bearing face 153a of the lug 153 bears on flat upper face of the stop lug 203. By this means the pins 168 are pushed up into their original positions as indicated in Fig. 8 with the ball 172 in engagement with the locking groove 169.

Various modifications may be made in the invention and the present exemplification is to be

taken as illustrative and not limitative thereof.

Having described my invention, I claim:

- 5 1. In a machine of the character described the combination of a supporting bracket, a guide sleeve having an opening therethrough integral with said bracket, and having bearing faces at its opposite ends, a pin slidably supported in the opening of the guide sleeve, a supporting leg hinged to said bracket and having a bearing face 10 at its upper end adapted to bear against one of the faces of said guide sleeve and one end of said pin, a locking heel integral with said leg, a separator plate in hinged connection with said supporting bracket and adapted to be positioned 15 between the adjacent faces of said guide sleeve and the bearing face of said supporting leg, a locking pawl hinged to said supporting bracket, a locking heel integral with said pawl adapted to lock with the locking heel of said supporting leg, 20 said pawl having a bearing face adapted to bear against the other face of said guide sleeve and also against the other end of said pin.
- 25 2. In a washing machine the combination of a normally horizontal platform, means on the platform to drive the appurtenances of the washing machine, a pair of supporting brackets supporting said platform, a guide sleeve integral with each supporting bracket, said guide sleeve having oppositely positioned bearing faces, a supporting leg hinged to each supporting bracket, each supporting leg comprising a vertical member and an inclined member, vertical upper and lower ribs at the opposite sides of the inclined member connecting it with the vertical member, 30 a locking heel and a bifurcated stop lug integral with the vertical upper rib of the inclined member of each supporting leg, a locking pawl hinged to each supporting bracket, a bifurcated locking heel at the swinging end of each pawl adapted 35 to ride on the upper vertical rib of the inclined member of its supporting leg, bumper heads extending from the vertical member of each supporting leg and a bumper foot extending from the lower end of the inclined member of each 40 supporting leg, said platform with its appurtenances adapted to be swung and folded with said supporting legs, said guide sleeves in said folded 45

position bearing on the bifurcated stop lugs of the inclined members of the supporting legs and the bifurcated locking heels of said pawls supported on the upper ribs of said inclined members.

5 3. In a washing machine the combination of a platform, an electric motor supported on the platform, an oscillating shaft journaled over the platform, connections between the motor and said shaft to oscillate the latter, a supporting collar 10 extending from one end of said oscillating shaft, said collar having flat side faces, a detachable cover over the platform, said cover comprising a front wall, side walls and a rear wall, an upper guide pin extending from the said front wall, 15 a bracket depending from said platform, a lower guide pin extending from said bracket, an upper oscillating beam having a vertical opening engaging the supporting collar extending from said oscillating shaft, a lower oscillating beam below 20 said upper beam, the lower oscillating beam having a vertical opening engaging said lower guide pin, stems hinged to the ends of the oscillating beams and a suction plunger connected to the lower end of each stem, the said upper oscillating beam adapted to be supported on said upper guide pin and said lower oscillating beam adapted to engage the supporting collar extending from 25 said oscillating shaft.

4. In a machine of the character described the 30 combination of a supporting bracket, a guide sleeve having an opening therethrough integral with said bracket, a pin slidably supported in the opening of the guide sleeve, a supporting leg hinged to said bracket, a locking heel integral 35 with said supporting leg, a separator plate in hinged connection with said supporting bracket adapted to be positioned between a face of the guide sleeve and the upper end of the supporting leg, a locking pawl hinged to said supporting 40 bracket and a locking heel integral with said pawl, the locking heel of the pawl adapted to be locked with the locking heel of the supporting leg, said pin adapted to bear between said supporting leg and said pawl to disengage the locking heels from each other.

CHARLES S. BOSSIE.
